(57) **CLAIM**

The ornamental design for an animal leash, as shown and described.

DESCRIPTION

FIG. 1 is a perspective view of an animal leash arranged in accordance with the present design;

FIG. 2 is another perspective view of FIG. 1;

FIG. 3 is a front elevation view of FIG. 1;

FIG. 4 is a back elevation view of FIG. 1;

FIG. 5 is a left side elevation view of FIG. 1;

FIG. 6 is a right side elevation view of FIG. 1;

FIG. 7 is a top plan view of FIG. 1;

FIG. 8 is a bottom plan view of FIG. 1;

FIG. 9 is a perspective view showing a portion of an animal leash in accordance with another embodiment;

FIG. 10 is another perspective view of FIG. 9;

FIG. 11 is a front elevation view of FIG. 9;

FIG. 12 is a back elevation view of FIG. 9;

FIG. 13 is a left side elevation view of FIG. 9;

FIG. 14 is a right side elevation view of FIG. 9;

FIG. 15 is a top plan view of FIG. 9; and

FIG. 16 is a bottom plan view of FIG. 9.

FIG. 17 is a perspective view showing a portion of an animal leash in accordance with another embodiment;

FIG. 18 is another perspective view of FIG. 17;

FIG. 19 is a front elevation view of FIG. 17;

FIG. 20 is a back elevation view of FIG. 17;

FIG. 21 is a left side elevation view of FIG. 17;

FIG. 22 is a right side elevation view of FIG. 17;

FIG. 23 is a top plan view of FIG. 17; and,

FIG. 24 is a bottom plan view of FIG. 17.

The features shown in broken lines in the various figures form no part of the claimed design. The shading shows contours, surfaces, or recesses of the present invention. The broken lines in the figures illustrate portions of the animal leash that form no part of the claimed design.

1 Claim, 9 Drawing Sheets
